DEPTH BOMB

Charles W. Bachert, Sr., and Charles W. Bachert,
Jr., Lafayette, La.

Application October 2, 1941, Serial No. 413,364

3 Claims. (Cl. 102—7)

This invention relates to depth bombs for the destruction of submarines, and has for the primary object the provision of a device of this character which is especially adapted for use by aeroplanes and like aircrafts to be dropped in a body of water within a reasonable distance of the submarine and includes a plurality of high explosive projectiles and a self submergible firing and propulsion device for discharging said projectiles in a plurality of different directions or courses from the submerging place in the body of water to better the chances of destroying the submarine by the different explosions from the various projectiles taking place in a much larger area than would be possible to accomplish by the explosion of a single submergible bomb or projectile, consequently reducing to a minimum the possibility of escape of the submarine undamaged.

With these and other objects in view as will become more apparent as the description proceeds, the invention consists in certain novel features of construction, combination and arrangement of parts as will be hereinafter more fully described and claimed.

For a complete understanding of our invention, reference is to be had to the following description and accompanying drawings, in which

Figure 1 is a side elevation illustrating a depth bomb in a submerged position within a body of water and constructed in accordance with our invention.

Figure 2 is a vertical sectional view illustrating the device.

Figure 3 is a sectional view taken on the line 3—3 of Figure 2.

Figure 4 is a sectional view taken on the line 4—4 of Figure 2.

Figure 5 is a vertical sectional view illustrating one of the projectiles and the portions of the firing means therefor.

Figure 6 is a fragmentary vertical sectional view illustrating a portion of one of the powder chambers and detonating cap therefor.

Referring in detail to the drawings, the numeral 5 indicates a self-submergible housing including angularly related walls providing to said housing sides 6, portions of which converge to present to said housing a tapered lower portion. The upper end of the housing is closed by a removable cap 7. The sides of the housing above the tapered portion are provided with openings in which are mounted powder chambers 8 extending radially from the vertical axis of the housing 5. Frictionally fitted within the powder chambers 8 are high explosive projectiles 9 sup-

ported horizontally by said chambers. The inner ends of said chambers arranged within the housing are substantially dome shaped and equipped with detonating caps 10.

5 It will be noted by referring to Figure 5 that the projectiles when mounted within the powder chambers do not entirely fill the spaces therein so that powder may be arranged therein to be set off by the detonating caps 10 when actuated by 10 firing pins 11 pivotally connected to the ends of radially extending arms 12 mounted on and secured to a shaft 13 journaled vertically in a bearing 14 supported by a spider 15 mounted in the housing 5. The shaft 13 is connected to the armature shaft of an electric motor 16 carried by 15 a support 17 in the lower tapered portion of the housing 5.

The electric motor 16 is connected in an electric circuit, the conductors of which are indicated 20 by the character 18 and also connected in the electric circuit is a source of electric energy 19 preferably in the form of a storage battery and a time control switch 20 of a conventional or well known construction mounted in a wall of the housing so that it can be adjusted and set in 25 operation exteriorly of the housing.

Normally the shaft 13 is positioned so as to hold the firing pins 11 in a retracted position.

Each projectile 9 includes a main cylindrical shaped shell 21 closed at one end by an end wall 22 and the opposite end closed by a removable tapered plug 23 of sectional formation.

A firing pin 25 is slidable in the plug 23 and has a headed end 26 arranged in advance of the plug 35 and is engageable with auxiliary firing pins 23' which engage detonating caps 27 arranged in communication with the chamber 24. The firing pin is spring influenced, as shown at 28.

40 Removably mounted within the shell 21 is a compressed air chamber 30 by having its open end threaded in a recess provided in the end wall 22 of said shell 21. A spring influenced plunger 31 is operable in the compressed air chamber 30, the stem 32 of which operates in 45 a guide 33 forming an integral part of the compressed air chamber and in which is located a coil spring 34 acting to urge the plunger in the direction of the wall 22 of the shell 21. The plunger 31 is held in the position shown in Figure 50 5 by the compressed air within the chamber 30. A suitable inflating valve 35 arranged in the end wall 22 of the shell and communicates with the compressed air chamber 30 so that the latter may be furnished with compressed air from any 55 suitable air supply source before the mounting

of the projectile 9 in a powder chamber of the housing 5. The major portion of the chamber 30 is spaced from walls of the shell 21 to provide in the latter a chamber 33 in which is located high explosive such as T. N. T. The walls of the compressed air chamber 30 have mounted therein detonating caps 37 exploded by firing pins 38 pivotally mounted within the compressed air chamber and actuated by the movement of the plunger 31 under the action of the spring 34. The detonating caps 37 are for the purpose of exploding the charge within the chamber 33 of the shell.

The wall 22 has a fragile or destructible portion 33' and a plunger 39 engageable therewith, the head of which is arranged in the powder chamber 3 so that when an explosion occurs therein for propelling the shell 21 or the projectile 9 in entirety the plunger 39 will be caused to rupture the fragile portion 33 and permit a gradual escape of the compressed air within the air chamber 30 and as the air pressure decreases the spring 34 acts to shove the plunger 31 to actuate the firing pins 38 and explode the detonating caps 37 and thereby explode the high explosive charge within the chamber 33 of the shell for the destruction thereof and a submarine in close proximity thereto. However, should the detonating caps 37 fail to fire or set off the highly explosive charge, the shell or projectile will be exploded on contact with the submarine or object by the firing pin 25 engaging therewith and actuating the detonating caps 27 bringing about a destruction of the plug 23 and exploding of the charge within the shell 21.

As before stated, the projectiles 9 mounted within the powder chambers 8 are supported horizontally and extend in a plurality of directions from the housing 5 due to the shape of the latter and the arrangement of the powder chambers therein so that when the powder within the powder chambers is exploded through the operation of the firing pins 11 by the electric motor under the control of the time switch 20, the projectiles will travel each in a different direction from the housing 5. As before described, the projectiles on leaving the powder chambers under the explosions therein will have the portions 33 ruptured to allow the compressed air to escape and bring about action of the plungers 31 on the firing pins 38 to fire the high explosive charge after the travel of the projectiles a distance from the point of location of the housing 5 so that the several explosions created by said projectiles will take place in a comparatively large area to increase the chances of destruction of a submarine over that obtainable by the explosion of a single projectile.

The cap 7 carries a cradle 40 including a series of curved arms 41 coactive in forming a seat for a spherical shaped float 42 in which is journaled a drum 43 having wound thereon a cable 44. The cable extends through a hole 45 provided in the float and has a series of branch cables 46 connected thereto. The branch cables are connected to eyes 47 provided on the powder chambers 8. The float 42 is equipped with keepers 47' engaged by pivotally mounted latches 48 carried by the cradle 40 or the arms 41 thereof. Floats 49 form integral parts of the latches and also act normally to sustain the latches in engagement with the keepers until contacted with water whence they disengage the latches from the keepers freeing the float 42 from the cradle, per-

mitting the housing 5 to sink by gravity in the body of water, the cable limiting the distance in which the housing 5 carrying the projectiles may submerge. However, when the device in entirety 5 is dropped into the body of water by an aeroplane or like aircraft the time switch 20 is previously set in operation so that the gun powder of the powder chambers which support the projectiles will be exploded after the housing 5 has sunk a distance below the surface of the water and before reaching its lowermost submerged position controlled by the cable and the float 42.

Thus it will be seen that the expulsion of the projectiles can to a reasonable amount be governed to a selected depth within a body of water.

The float 42 is provided with a small port 50 through which air may escape as the float fills with water by way of the opening 45 so that the float will sink after the float has been in the water for a period of time.

The reason for the sinking of the float 42 is to prevent the device from falling in the hands of an enemy or interfering with shipping. Of course, the phase of bringing about the sinking 25 of the float and allowing the housing 5 to sink to the bottom of the body of water is only incidental as far as the present invention is concerned and if desired may be eliminated by omitting the port 50 from the float so that the float 39 may continue to support the housing 5 in order that it may be recovered at a later time and again used for the discharge of other projectiles.

While we have shown and described the preferred embodiment of our invention, it will be understood that minor changes in construction, combination and arrangement of parts may be made without departing from the spirit and scope of the invention as claimed.

Having thus described the invention, what we claim is:

1. In a depth bomb, a sinkable firing and propulsion device including a plurality of explosion chambers extending in various directions therefrom and containing explosive material and including detonating caps, projectiles mounted in said explosion chambers to be projected by the force of the explosions therein in various directions from said device and each including means for the explosion thereof after traveling a distance from said device and actuated by the force of the projecting explosion, a flexible element connected to said device, a drum having said flexible device wound thereon, a buoyant float housing said drum, and float actuated latches for releasably securing the float to said device.

2. In a depth bomb, a sinkable housing, explosion chambers carried by and extending in various directions from said housing, time controlled mechanism for the firing of explosive within the explosion chambers, explosive projectiles mounted in said chambers to be fired therefrom by the force of the explosions and each including an explosive chamber, an air compression chamber, a spring influenced plunger operating in said air compression chamber, detonating means actuated by said plunger on the release of air pressure from said air compression chamber, and means for the discharge of the air pressure from the air compression chamber and operated by the force of explosions expelling the projectile from the firing chamber.

3. In a depth bomb projectile, a shell, a contact type detonating means carried by said shell and located at one end thereof, an air compres-

sion chamber in said shell and coacting therewith in defining an explosion chamber, means for admitting air pressure to said chamber, a spring influenced plunger operable in said air compression chamber and affected by the air pressure, detonating means operated by said plunger on the decrease of air pressure in said air compression chamber and carried by the lat-

ter for exploding the discharge within the explosion chamber of the shell, and means carried by said shell for venting the air pressure chamber and actuated by a force of explosion propelling said shell.
